Inventor

John E. Shepherd,

By George Bain, Atty.

UNITED STATES PATENT OFFICE.

JOHN E. SHEPHERD, OF CHICAGO, ILLINOIS.

THERMOSTAT.

SPECIFICATION forming part of Letters Patent No. 784,186, dated March 7, 1905.

Application filed April 25, 1904. Serial No. 204,778.

To all whom it may concern:

Be it known that I, JOHN E. SHEPHERD, of Chicago, in the county of Cook and State of Illinois, have invented certain new and useful 5 Improvements in Thermostats; and I hereby declare that the following is a full, clear, and exact description thereof, reference being had to the accompanying drawings, which form part of this specification.

10 My invention relates to improvements in thermostats adapted for use in conjunction with electric signaling systems, such as fire-alarm systems and the like; and it has for its primary object to provide a device of the character described which is simple in construction and efficient in operation.

Other and further objects will become apparent from the following description, taken in conjunction with the drawings, wherein—
20 Figure 1 is a horizontal section of a thermostat, taken on line 1 1 of Fig. 2. Fig. 2 is a vertical section on line 2 2 of Fig. 1. Fig. 3 is a detail of one form of circuit-controlling mechanism, and Fig. 4 is a detail of a slightly-
25 modified form of circuit-controlling mechanism.

Throughout the drawings like numerals of reference refer always to like parts.

In the drawings, 5 indicates an insulating-
30 casing, preferably comprising a substantially oblong body part having a flat bottom 6, in the center of which is formed a depression or well 7.

8 is a central perforation in the bottom of
35 the well-wall.

9 and 10 indicate opposing metallic strips or springs arranged end to end in longitudinally-separated relation and suitably secured upon the flat bottom 6 of the thermostat-casing, so that their line of separation is over the well 7. 9' and 10' indicate similar metallic strips arranged in parallelism to the strips 9 and 10 in like relation. The strips 9 and 10 are adapted to be included in one circuit of a
40 system and the strips 9' and 10' in another circuit of the system. Associated with these parts is a circuit-controlling means of the thermostat, comprising movable parts adapted to normally close the circuits through the

strips 9 and 10 and 9' and 10', and when moved 50 in operation to first break the circuit continuity through said strips and subsequently to reestablish the same and also establish an electrical cross connection between the circuits comprising said strips. In the construction 55 shown 11 is a vertically-disposed rod having attached thereto two cross-bars, generally indicated by the numerals 12 and 13. These cross-bars are preferably of wedge shape in cross-section arranged with their apexes in 60 confronting relation and disposed in the casting so that the cross-bar 12 lies beneath the circuit-strips and the cross-bar 13 lies thereabove, both in vertical alinement with the separating-space between the strips of the respective pairs. The cross-bar 12 comprises a central portion 14, of insulating material, secured to the rod and having affixed to its ends metallic conducting-pieces 15 and 15', adapted to make contact, respectively, with 70 the strips 9 10 and 9' 10'. The cross-piece 13 in the form shown in Fig. 3 is a continuous metallic member uninterrupted by insulation; but it may be, as illustrated at 13' in Fig. 4, composed of a central insulation-section 16 75 and metallic pieces 17 17', separated by said insulation-section. Normally the cross-bar 12 of the circuit-controlling member is forced between the circuit-strips 9 10 and 9' 10', so that its conducting portions 15 15' complete 80 the circuit through the said pairs of strips. The parts are held in such position by a body 18 of fusible material, such as solder, joining the vertical rod 11 and the casing member. Preferably said body of material is 85 on the outside of the casing at the bottom of the well, as indicated in Fig. 2. The arrangement of the device is such that the stem 11 constantly tends to move in such direction as to bring the upper cross-bar 13 into contact 90 with the circuit-strips, in the present embodiment such tendency being due to the action of gravity.

19 is a weight rigidly affixed to the stem 11 and arranged within the well 7, near the upper 95 part thereof, to insure movement of the stem when the material 18 is fused. It will be apparent, however, that a spring might be sub-

stituted for the weight 19, if desired, so that the device would move independently of gravity, or that the two might be used conjointly.

In operation the parts are set in a position as indicated until the heat conditions become such as to fuse the body of solder 18 and release the rod 11 from its restraint against downward movement. At such time under the action of the weight 19 the rod 11 descends, carrying with it the cross-bars, so that the metallic portions 15 15' of the cross-bar 12 leave contact with the circuit-strips and break both circuits through the thermostat. Immediately thereafter the upper bars 13 and 13' come into contact with the circuit-strips to complete the circuits through both wires leading into the thermostat. In the event the form of circuit-controlling means shown in Fig. 4 is used, however, the thermostat-circuits are first broken through both wires and reestablished, while if the form illustrated in Fig. 3 be employed the reestablishment of the circuits following the double break is accomplished by the establishment of a cross connection between the two thermostat-wires.

While I have illustrated and described in detail an operative embodiment of my invention, it will be apparent that slight changes might be made therein without departing from the spirit and scope of my invention.

Having described my invention, what I claim, and desire to secure by Letters Patent of the United States, is—

1. In a thermostat, separated parts adapted to be included in two electric circuits, a circuit-controlling means associated therewith, comprising a movable member, means associated therewith for independently completing circuits through the circuit parts when the movable member is in normal position, and to break both circuits when the movable member is moved, means arranged to close the circuit subsequent to the breaking thereof by the first-named means when the movable member is moved, and fusible means for normally holding the movable member against movement.

2. In a thermostat, separated parts adapted to be included in two circuits, circuit-controlling instrumentalities comprising movable means arranged when in normal position to close the circuits through said circuit parts and movable to break the circuits therethrough, other means normally disconnected from said circuit parts movable to reestablish circuit through said parts, after the rupture of the circuit by the first-named movable means, and means for normally holding said circuit-controlling instrumentalities against movement.

3. In a thermostat, separated parts adapted to be included in two electric circuits, a circuit-controlling structure comprising means for normally closing the circuits through said

circuit parts, other means adapted to close said circuit parts normally disconnected from the same, and a means for moving said circuit-controlling structure to break the connection of the first said means with the circuit parts and subsequently make connection of the second said means with the circuit parts, and means for normally holding said structure against movement.

4. In a thermostat, the combination with circuit parts of means normally closing circuits through such circuit parts arranged for movement to break connection between the same, means normally out of connection with said circuit parts movable to reestablish circuit connections between the same subsequently to the operation of the first said means, and a body of fusible material for holding said circuit-controlling parts normally against movement.

5. In a thermostat, a casing, circuit-strips arranged within the casing in a plurality of parallel pairs, adapted to constitute parts of a plurality of circuits, the strips of each pair being separated, a structure comprising two vertically-separated cross-bars one normally arranged to establish connection independently between said pairs of strips, and adapted when the structure is moved downward to break connection between said strips, and the other normally out of contact with said strip arranged when the structure is moved downward to break connection between said strips, and the other normally out of contact with said strip arranged when the structure is moved downward to make electrical contact therewith, and heat-releasable means for holding said structure against movement.

6. In a thermostat, a plurality of pairs of separated circuit-strips each pair adapted to constitute part of an electric circuit, a circuit-controlling structure comprising two circuit-closing bars one provided with conducting portions insulated from each other normally arranged to close the independent circuits through said pairs of strips, and the other bar providing electrically-connected portions normally disconnected from the circuit-strips, said structure being movable to first disconnect the first said bar from the circuit-strips, and subsequently connect the second-mentioned bar with said strips, and heat-releasable means for normally holding the circuit-controlling structure against movement.

7. In a thermostat, separated parts adapted to be included in an electric circuit, circuit-closing means normally making connection between said circuit parts and movable to break connection therebetween, another circuit-closing means normally out of connection with said circuit parts movable to make connection therebetween subsequently to the breaking of the connection by the first said means, and means for normally holding said

circuit-closing means against movement, thermally operable to release said circuit-closing means.

8. In a thermostat, the combination of the following instrumentalities, to wit; separated circuit-strips, a structure arranged for movement when unrestrained comprising two separated conducting - pieces adapted to successively complete the circuit when moved, and 10 heat - releasable means for restraining said

structure against movement with the first-acting of said conducting - pieces in circuit-closing position.

In testimony that I claim the foregoing as my own I affix my signature in presence of two 15 witnesses.

JOHN E. SHEPHERD.
